Jack T. Hanby, 902 N. Springfield, Berryville, Ark.

Filed Mar. 12, 1962, Ser. No. 69,199

Term of patent 7 years

(Cl. D12—2)

Fig.2.

Fig.3.

FIG. 1 is a perspective view of a poultry feeder, showing my new design;

FIG. 2 is a front elevational view thereof; and

FIG. 3 is an end elevational view of the poultry feeder.

The rear of the poultry feeder is substantially the same in appearance as the front and the undisclosed end is like the end shown.

I claim:

The ornamental design for a poultry feeder, as shown and described.
